CLAIM

The ornamental design for a radio receiver, as shown
and described.

DESCRIPTION

FIG. 1 is a front perspective view of a radio receiver
showing my new design;

FIG. 2 is a rear perspective view with the telescoping
antenna in a stowed position inside the receiver;

FIG. 3 is a fragmentary perspective view of part of the
front near the top right corner;

FIG. 4 is a fragmentary perspective view of the rear top
left corner; and

FIG. 5 is a fragmentary perspective view at the location
where the front, top and left side meet.

FIG. 3

FIG. 4

FIG. 5
